UNITED STATES PATENT OFFICE.

HARRISON D. McFADDIN, OF EAST ORANGE, NEW JERSEY.

LAMP-FIXTURE.

1,090,929.

Specification of Letters Patent. Patented Mar. 24, 1914.

Application filed March 31, 1913. Serial No. 757,804.

To all whom it may concern:

Be it known that I, HARRISON D. McFADDIN, a citizen of the United States, residing in the city of East Orange, county of Essex, and State of New Jersey, have invented a certain new and useful Lamp-Fixture, of which the following is a specification.

This invention is a lamp bracket intended, more particularly, for use with bed lamps, its function being that of securing a lamp to a bed-post, or analogous supporting means, in a simple, efficient and secure manner.

The invention embodies, also, improvements wherein the lamp may be mounted on either a vertically or horizontally extending portion of the bed and securely locked against displacement.

From a more specific standpoint, the invention is particularly designed for supporting a lamp on metallic bedsteads, and, as the posts of such beds vary in shape, the present invention embodies means whereby the bracket or fixture readily adapts itself to all such shapes ordinarily employed.

Other features and advantages will be apparent from the following detailed description read in conjunction with the accompanying drawings. In said drawings, one practical embodiment of the invention and the application thereof to supports of different shapes, is shown, but these drawings are to be understood as illustrative, only, and not as defining the scope or limits of the invention.

Figure 1 is a perspective view showing a lamp fixture of the present invention in place upon a vertically-extending circular post of a metallic bedstead. Fig. 2 is a central, horizontal section through the fixture. Fig. 3 is a central, vertical section thereof. Fig. 4 is a plan view showing the application of the fixture to a horizontally disposed supporting member. Figs. 5 and 6 are fragmental sections, similar to the section shown in Fig. 2, illustrating the application of the fixture to bed-posts, or other supporting means, of varying shapes. Fig. 7 is a perspective view of a threaded nut which is employed.

In said drawings, A denotes a casing which, although shown rectangular in cross-section, may, in some cases, be varied, as will hereinafter be more fully described. The casing is made open at both ends, and

into its forward end is adapted to be fitted the shank b^2 of a plug B, which plug carries the illuminating means. As the embodiment of the invention shown is more specifically adapted for use in combination with electric fixtures employing my well-known "Emeralite" shades, and, since these shades are of elongated shape, as shown in dotted lines in Fig. 1, the plug B is provided with laterally extending arms C, C', to which the lamp shade is secured by any well-known means.

The electric lamp (not shown) which furnishes the light is supported in the usual socket which screws onto the nipple c' , at the outer end of the arm C, and the electric wires w , for furnishing the power to said lamp are led through a hole a , in the casing, forwardly therethrough, and from thence to the lamp through a duct c , provided for this purpose within the plug B and the arm C.

The casing A, is enlarged at the rear end thereof, as at D, so as to give additional thickness of material and consequent increase of strength at this point. Two opposite sides of this enlarged portion D, are cut away, at d' , leaving the portion D composed of merely two rearwardly extending parallel flanges d , d . A flexible strap E, substantially equal to, or less in width than, the inner dimension of the casing B, is adapted to lie intermediate its length, between the flanges d , in such a manner as to lie flat across the open end of said casing. Moreover, the strap is provided with an aperture e , at such intermediate point, so that, when positioned as aforesaid, said aperture will lie in the medial line of the casing.

The plug B, which closes the front end of the casing, is, like the strap E, apertured in the central medial line of the casing. A bolt F is passed through the aperture b' , in the plug B, longitudinally through the casing A, through the aperture e , in the strap, beyond which it threads into a nut G. This nut is cut away, as at g , so as not to interfere in its operation with the wires w which supply the electric current to the lamp. Thus, if the bolt is turned to draw the nut into the casing, the strap will be drawn therewith. The free ends of the strap co-operate with one another to form a catch member e' .

The operation of the device, thus far described, is as follows:—The free ends of the

strap are passed about a bed-post, or other support, the ends thereof being secured together by the catch member e' . While the bolt F is being turned to draw the nut G into the casing A , this nut is carrying a portion of the strap with it, thereby causing the remaining portion thereof to be tightly wrapped about the supporting post, and the enlarged end of the casing to be brought into gripping engagement with said support. In other words, the casing is drawn tightly against the support as a result of the pull exerted upon the strap by the bolt, whereby said pull operates to securely retain the fixture on the support.

A salient feature of the invention is its adaptability for application on supports of various shapes. Figs. 2, 5 and 6 illustrate its application to the cross-sections most generally employed in bedstead construction, said figures clearly showing how the flexible strap adapts itself to the shapes illustrated. Moreover, certain details of construction are provided to insure proper engagement between the fixture and its support. More specifically speaking, the fixture is very well adapted to engage with a round section X , Fig. 2, by virtue of a pair of clamping jaws I, I' , which are disposed in parallel relation to one another, on a pair of pivoting pins i, i' , fixed between the flanges d, d of the enlarged portion of the casing. Looking at Fig. 2, it will be seen that, when the strap is drawn into the casing, it is just stiff enough to lend itself to an easy curve which engages with the clamping members I, I' , and forces said members into engagement with the support. Thus, when the bolt is screwed up tightly, the pull on the strap will be shared by the pins i, i' , and said strap.

While the clamping means, just described, is highly meritorious in providing engaging means which will not scratch or dent the support, I wish it understood that its use is not compulsory to the satisfactory operation of the fixture and that, if desired, it may be dispensed with.

The application of the bracket to a support presenting a flat face is clearly illustrated in Fig. 6, which shows how the flat ends of flanges d, d on the enlarged portion D of the casing furnish a maximum bearing surface against the side of the square section X^2 . In Fig. 5, it is clearly evident that the ends of the flanges d may be notched, as at d^3 , to coöperate with a support presenting a corner, as the diamond-shaped section X' . In the two last described applications of the device, the clamping members I, I' do not play so important a part as in the first application, but, if the fixture embodies the clamping members, the flat ends and the notches i, i' , therein, it is obviously adapted for engagement with almost every

conceivable shape. Furthermore, as the strap may be drawn into the casing to varying extents, it is manifest that the fixture may be secured on supports of diverse sizes.

Now, referring, more particularly, to Fig. 3 of the drawings, it will be noted that the aperture b , in the plug B , is countersunk, as at b' , to receive the head f , of the bolt and thus render it inaccessible to inquisitive persons who might be apt to tamper with it, and thus loosen the bracket from its support. Accordingly, in practice, the bolt head f , is preferably made polyhedral and is adjusted by means of a key or wrench (not shown) similar to a bed wrench. Moreover, the operation of the device is greatly facilitated if the bolt is fixed against longitudinal movement, so that, when unscrewed, the strap E will be loosened and pushed out of the casing instead of the bolt backing out, as it would be apt to do. To this end, the head of said bolt is provided with a circumferential flange f' at the base of its polyhedral portion, and a pin or set screw f^2 is tapped into the plug in such a manner as to engage the outer face of said flange, thereby holding the bolt against withdrawal.

As before stated, and clearly shown in dotted lines in Fig. 1, the lamp shade which I prefer to employ has an elongated horizontal axis. Accordingly, it is requisite to the proper mounting of this shade that the arms C, C' , on the plug B , are, when the bracket is fixed to its support, in a substantially horizontal plane. In view of this requirement and the further fact that I desire to provide a fixture which may be secured to either a vertically or horizontally disposed portion of a bedstead, the fixture allows of the adjustments next to be described.

If the fixture is in the position shown in Fig. 1 of the drawings, *i. e.*, on a vertical post of a bedstead, and it is desired to transfer it to a horizontally disposed portion of said bedstead, the bolt F is loosened, and the catch members e' disengaged from one another to detach the fixture from the bed-post. The shank b^2 , of the plug, which is loosely fitted into the forward end of the casing B , may now be withdrawn therefrom and out of engagement therewith (see dotted lines in Fig. 3), after which said plug may be given a quarter turn and then inserted again into the end of said casing. The fixture may now be secured to the horizontal support, as shown in Fig. 4, in the manner hereinbefore described. The foregoing adjustment is, because of the rectangular cross-section of the casing shown, limited to the variations of ninety degrees. It will be manifest, however, that, if the forward end of said casing were made polyhedral and the stem of the plug correspondingly formed, the scope of adjustment would be increased.

directly proportionate to the number of sides provided. Thus, the fixture might be positioned on a support disposed at almost any angle to the horizontal plane of the shade-supporting arms.

Throughout the foregoing description, and in the drawings, but one embodiment of the invention is considered and, among other things, the specific mounting of a shade of particular form is pointed out. It is not intended, however, to limit the invention to this embodiment, as, obviously, this detail of construction might be varied. I may, if desired, mount a lamp directly upon the plug and, moreover, dispense with the shade. These features are immaterial. Therefore, for these and other obvious reasons, I do not wish to be understood as limiting myself any further than the state of the art may require.

While the invention has been particularly described with reference to its employment as a lamp bracket, it will be understood, of course, that certain parts thereof are equally adapted for use in analogous relations.

Having thus fully described the invention, what I claim as new, and desire to secure by Letters Patent is:—

1. In a lamp bracket, the combination of a substantially closed casing, a flexible clamping strap coöperating therewith and adapted to engage a bed-post or other support, and means for drawing a portion of the strap within the casing whereby said strap is tightly wrapped around the supporting post.

2. In a lamp bracket, the combination of a casing, a flexible clamping strap positioned at one end thereof, said strap being adapted to engage a bed-post or other support, a threaded spindle extending longitudinally through the casing from the end opposite that whereat the strap is positioned, and a threaded member in engagement with said strap and operating with the threaded spindle whereby a portion of the strap may be drawn within the casing for tightly wrapping said strap about the supporting post.

3. In a lamp bracket, the combination of a casing open at both ends, a clamping strap coöperating with one end of the casing and adapted to engage a bed-post or other support, an apertured plug at the opposite end of the casing adapted to carry a lamp, a threaded spindle extending through the aperture in the plug and longitudinally of the casing into operative relation with a threaded nut coöperating with the flexible strap, whereby the turning of said threaded spindle will operate to draw a portion of the strap within the casing and tightly wrap it about the supporting post.

4. In a lamp bracket, the combination of a casing, a flexible strap coöperating therewith and adapted to engage a bed-post or

other support, a threaded member within the casing for the purpose of tightly wrapping said strap about the supporting post, and clamping members mounted on the casing for coöperation with said post, said members being so positioned that the tension on the strap will force them into rigid engagement with the supporting post.

5. In a lamp bracket, the combination of a casing, a flexible strap coöperating therewith and adapted to engage a bed-post or other support, a threaded member within the casing for the purpose of tightly wrapping said strap about the supporting post, and a pair of clamping members pivoted on the casing for coöperation with said post, said members being so positioned that the tension exerted by the pivoted member upon the strap will force the clamping members into rigid engagement with the supporting post.

6. In a lamp bracket, the combination of a casing, a flexible strap coöperating with one end thereof and adapted to engage a bed-post or other support, a light-bearing member at the other end of the casing, and a threaded member coöperating with the light-bearing member and the flexible strap whereby the operation of the threaded member in one direction will cause the light-bearing member to be fixedly positioned at its respective end of the casing and simultaneously draw a portion of the flexible member within the casing for the purpose of tightly wrapping the remainder thereof about its support, while the operation of said threaded member in the opposite direction operates to loosen the flexible strap from about its support and simultaneously loosen the light-bearing member to such extent that it is capable of angular adjustment.

7. In a lamp bracket, the combination of a casing, a flexible strap coöperating with one end thereof and adapted to engage a bed-post or other support, a light-bearing plug detachably connected to the other end of said casing, and a threaded bolt connecting the plug and the nut coöperating with the flexible strap whereby the screwing up of said bolt will operate to firmly seat the plug on its respective end of the casing and, at the same time, cause a portion of the strap to be drawn into the opposite end thereof for the purpose of wrapping the remainder of said strap tightly about the supporting post.

8. In a lamp bracket, the combination of a casing, said casing having an opening therein through which electric wires may be led into the casing, a flexible strap coöperating with one end thereof and adapted to engage a bed-post or other support, an apertured plug detachably seated at the opposite end of said casing, a threaded bolt extending through the aperture in the plug longitudi-

nally of the casing and threading into a nut coöperating with the flexible strap whereby the screwing up of said bolt operates to seat said plug in its respective end of the casing 5 and simultaneously draw a portion of the strap into the opposite end thereof whereby the remaining portion of said strap is tightly wrapped around its support, and laterally extending arms positioned on the aforesaid 10 plug for supporting a shade and lamp, one of said arms being provided with a duct

through which the wires for carrying the current for said lamp may be led thereto, after entering the casing through the aforesaid aperture therein. 15

In testimony whereof I have signed my name to this specification in the presence of two subscribing witnesses.
